Ralph A. Muscatiello, Norwood, Mass., assignor to The Gillette Company, Boston, Mass., a corporation of Delaware

Filed Dec. 20, 1961, Ser. No. 67,988

Term of patent 14 years

(Cl. D58—12)

FIG. 1

FIG. 2

FIG. 4

FIG. 1 is a top plan view of a display case for safety razor and blades, showing my new design,

FIG. 2 is a view in side elevation thereof,

FIG. 3 is an end view of the case as seen from the right of FIG. 2, and

FIG. 4 is a view of the case in cross section on the line 4—4 of FIG. 2.

The side and end of the display case not shown are substantially the same as the respective side and end shown in FIGS. 2 and 3.

I claim:

The ornamental design for a display case for safety razor and blades, substantially as shown and described.
